UNITED STATES PATENT OFFICE.

DANIEL F. HAVERSTICK, OF TRENTON, NEW JERSEY.

FLOOR-COVERING.

1,225,954.

Specification of Letters Patent. Patented May 15, 1917.

Application filed May 17, 1916. Serial No. 98,009.

To all whom it may concern:

Be it known that I, DANIEL F. HAVERSTICK, a citizen of the United States, residing in the city of Trenton, county of Mercer, 5 State of New Jersey, have invented certain new and useful Improvements in Floor-Coverings, of which the following is a specification.

In the manufacture of oil cloth, linoleum, 10 cork carpet and similar floor coverings it has been customary heretofore to use felt or similar paper as a backing. This backing of paper usually is saturated with some sort of water proofing solution, such as tar. One 15 surface of such paper backing is provided with a coating of ordinary varnish on to which the final coating or layer of pigment, linoleum material or cork compound is placed to complete the manufacture.

20 The layer or coating of varnish now in general use has been found to be objectionable and unsatisfactory in that it is somewhat lacking in body and is also brittle and renders the product more or less stiff and 25 inflexible. By reason of its brittleness, it is also found that it fails to act satisfactorily to prevent the water proofing material with which the paper or other backing of suitable material is saturated from passing through 30 and showing upon the surface of the oil cloth, linoleum or other sheet material and thereby injuring the appearance and selling quality of the covering.

One object of my invention is to provide 35 a floor covering which is relatively flexible and in which the intermediate coating or layer of impervious varnish is more pliable and flexible than that which heretofore has been used and which is not brittle and therefore will not crack and permit the passage 40 therethrough of the water proofing material with which the backing sheet is saturated to pass through and show upon the surface of the covering.

45 I have discovered that when either Manila copal or acaroid resin in a solution of alcohol is employed to form the intermediate coating or layer upon the backing, such layer or coating has more body, is more flexible and does not crack, so that a greatly improved article results. I have also discovered that these two substances, Manila copal and acaroid resin, may be used to great advantage when mixed in any desired proportion 50 and dissolved in alcohol and used in

like manner as either alone may be used when dissolved as described.

Other objects and advantages of my invention will be referred to and pointed out in the description thereof which follows or 60 will be apparent from such description.

For the purpose of enabling my invention to be more easily and readily understood, I shall describe the same in connection with the accompanying drawing in which the relation of the elements entering into the manufacture of floor coverings embodying my invention are indicated, but I desire it to be understood that my invention is not limited to a construction in which the backing 70 consists of any specific form of sheet material or in which the top layer of material constituting the top or wearing surface consists of any specific or particular form of material.

75 In the drawing,—

Figure 1 is a transverse sectional view through a portion of a sheet of oil cloth; and Fig. 2, is a transverse sectional view through a portion of a sheet of linoleum.

80 Referring to the drawing, 1 designates a sheet of backing material consisting, in the construction as illustrated, of felt paper, saturated with a solution of any suitable water proofing material, such as tar. Although sheet 1 is described as consisting of felt paper, it should be understood that it may consist of any other sheet material suitable for use in the manufacture of floor or other coverings. 2 designates a layer 85 consisting of either Manila copal or acaroid resin alone or mixed in any desired proportions, the same having been applied while in a solution of alcohol. In other words, either of these substances or a mixture thereof is dissolved in alcohol to form a solution, which solution is applied in any known manner to one surface of the sheet 1.

90 Referring to Fig. 1, 3 designates a layer of any known flexible material such as is in general use or which is suitable for use in the manufacture of oil cloth.

95 In Fig. 2, 4 designates a relatively thick layer of linoleum material. Both layers 3 and 4 are applied on top of the layer 2 and 100 constitute the tops or wearing surfaces of the floor coverings illustrated in Figs. 1 and 2 of the drawing.

105 As above stated, I have discovered that when either Manila copal or acaroid resin 110

- or a mixture thereof is dissolved in alcohol and employed to form the intermediate layer 2, such layer possesses a better body than when ordinary varnish is employed.
- 5 It is also more elastic and more flexible and its quality of insulation is superior to that of the ordinary varnish heretofore used in the manufacture of coverings of the character herein referred to and contemplated.
- 10 By thus providing an intermediate layer having the characteristics specified a covering is produced in which the top coating or layer such as 3 or 4 illustrated in the drawing is protected from the water proofing material with which the backing sheet 1 is saturated or from any other injurious substance which might, but for the presence of the intermediate layer 2, come into contact with the said layers 3 and 4, and which
- 15 20 might cause discoloration of the top or wearing surface thereof.

Although I have illustrated in the drawing only oil cloth and what is commonly known as linoleum and have described my invention in connection therewith, it is to be understood that the materials to which I have referred and the advantages of which have been particularly pointed out in connection with the drawings may be employed 25 also to constitute and form the intermediate protecting layers in any other coverings than those illustrated where such intermediate protecting layers may be employed to advantage.

30 35 I claim:

1. As an article of manufacture a com-

posite sheet material comprising a backing of relatively tough fibrous material rendered water proof by a water proofing substance, a layer of varnish comprising a mixture of 40 Manila copal and acaroid resin and a top or surface layer of flexible material upon the said layer of varnish.

2. As an article of manufacture a floor covering comprising a backing of suitable 45 fibrous sheet material saturated with a water proofing substance, an impervious layer of flexible material comprising Manila copal fixed to the said backing sheet and a top or surface layer of flexible material upon the 50 layer of Manila copal.

3. As an article of manufacture a floor covering such as linoleum, cork carpet or oil cloth comprising a backing sheet of porous material saturated with water-proofing substance, a layer or coating of material upon the said backing sheet, said layer or coating comprising Manila copal and a top or surface layer of flexible material upon the said 55 layer of Manila copal.

4. As an article of manufacture a floor covering such as linoleum, cork carpet or oil cloth comprising a backing sheet of porous material, a layer comprising Manila copal affixed to said sheet and a top or surface layer of flexible material upon said 60 layer of Manila copal.

In testimony that I claim the foregoing as my invention I have hereunto signed my name this 10th day of May, A. D. 1916.

DANIEL F. HAVERSTICK.
